United States Patent

Des. 235,772
Patented July 8, 1975

235,772

AERATOR

Dominic Anthony Saporito, Fanwood, N.J., assignor to
American Standard Inc., New York, N.Y.

Filed Feb. 20, 1973, Ser. No. 334,161

Term of patent 14 years

Int. Cl. D23—01

U.S. Cl. D23—35

FIG. 1

FIG. 2

FIG. 3

FIG. 1 is a front perspective view of an aerator embodying my new design, as seen from a position beneath the aerator;

FIG. 2 is a bottom plan view thereof; and

FIG. 3 is an elevational view thereof.

I claim:

The ornamental design for an aerator, substantially as shown and described.
